UNITED STATES PATENT OFFICE.

CHARLES PASCAL, OF MONTREAL, QUEBEC, CANADA, ASSIGNOR TO PASCAL RAIL JOINT COMPANY, INC., A CORPORATION OF NEW YORK.

ELECTRIC CONNECTER IN RAIL JOINTS.

Application filed June 17, 1922. Serial No. 569,106.

The invention relates to electric connector in rail joints as described in the present specification and illustrated in the accompanying drawings that form part of the same.

The invention consists essentially of the novel features of construction pointed out broadly and specifically in the claim for novelty following a description in detail of the preferred form of the invention.

The objects of the invention are to furnish in electric and steam railway lines a joint in which the rails will be electrically connected by members intimately associated with the joint members; to facilitate the construction of railway lines by eliminating the labor incidental to what is familiarly known as bonding the rails; to reduce the cost of maintenance by protecting the electrical connectors from accidental or wanton destruction and thereby insure safety to life and property; and to provide a safe, durable and efficient electric connection in rail line joints.

In the drawings, Figure 1 is a perspective view of the rail joint showing the rail in cross section and broken away to disclose the connector member.

Figure 2 is a perspective detail of a base connector lower plate.

Figure 3 is a perspective detail of a base connector upper plate.

Figure 4 is a perspective detail of a base connector side strip.

Figure 5 is a cross sectional view of the joint showing another form of the plate connector.

Figure 6 is a detail of the modified joint plate.

Like numerals of reference indicate corresponding parts in the various figures.

Referring to the drawings, the rail joint is preferably formed on a base plate 1 having rail recess 2 between the recess 3 and abutment 4.

The electric conductor 5 in the form of a copper plate is laid on the base 1 and flanged over the ends of said plate forming the flanges 6 slotted at 7 for greater flexibility in installing the connector.

The rails 8 and 9 are laid on the copper plate 5 and the copper plate 10 is laid on

the upper side of the rail bases to one side of the web and has the flange 11 at its inner longitudinal edge. This plate 10 extends from the edge of the rail bases in the extra width 12 over the abutment 4 and terminates at the edge of the base plate 1, the extension 12 laying flat on the abutment in distinction from the upwardly inclined base portion 13 and at the outer edge being slotted at 14 and 15 for fastening bolts and flanged at the ends 16 and slotted at 17 in said flanges, the said flanges 16 being knocked over the ends of the base 1.

The side strip 18 of copper is inserted in the bed of the recess 3 and is flanged at the ends 19 and 20 against the ends of the base 1, thereby forming a partial encasement of the rails in copper and insuring a reliable electric connection from rail to rail, but it must be understood that all of these connectors are not always needed and one or more may be used according to the requirements.

In Figures 5 and 6 a different form of plate is shown and this is preferably used as a single connector 21 fitting under the rail base and extending around one end and over the rail base to the web and extending vertically up said web behind and under the joint plate and having flanges 22 and 23 at the ends with the slots 24.

The joint plate 25 is made to fit against the rail and extend outwardly over the rail base and base abutment and completely cover the copper plate therebelow having the corresponding bolt slots 26 and 27 through which the bolts 28 and nuts 29 fasten the said joint plate and copper conductor to the base 1 as well as closing in the filler key 30, which is wedged in between the rail base and abutment.

In installing this joint the base plate is mounted on the tie and the plate of copper or other suitable conducting metal is placed thereon and flanged over the ends. The ends of the rails are then placed together on top of this connector and the rail base against the connector formed on the side strip. The upper connector is then laid on the rail base and bolted thereto with the joint plate and flanged over the ends. There is thus a reasonably secured connection from

rail to rail which will be found equally efficient in steam and electric railways.

What I claim:—

In an electric connector in rail joints, a rail chair having an inturned flange forming a recess for the rail base and a conducting bar grooved longitudinally to fit in said

recess and on the rail base and having flanges turned over the ends of said chair base.

10

Signed at Montreal, Canada, this 9th day of June, 1922.

CHARLES PASCAL.
